EDWARD A. ROCK, OF LUDLOW, VERMONT.

Letters Patent No. 74,144, dated February 4, 1868.

IMPROVEMENT IN GLOBE STEAM-VALVES.

The Schedule referred to in these Letters Patent and making part of the same.

PRIOR TO THIS

TO ALL WHOM IT MAY CONCERN:

Be it known that I, EDWARD A. Rock, of Ludlow, in the county of Windsor, and State of Vermont, have invented a new and improved Valve; and I do hereby declare that the following is a full, clear, and exact description thereof, which will enable those skilled in the art to make and use the same, reference being had to the accompanying drawings, forming part of this specification.

The object of this invention is to form a valve for the stoppage and passage of steam, water, or gas, or other fluids or liquids, in such a manner that the constant use of the same shall not injure the joint or cause the valve to leak; and the invention consists in the arrangement of an open-ring valve on the valve-stem, which, when the valve is closed, shall be expanded by a stationary wedge in the valve-seat, as will be hereinafter described.

Figure 1 represents a longitudinal section of the valve through the line *xx* of fig. 2.

Figure 2 is a cross-section of fig. 1, through the line *yy*.

Similar letters of reference indicate corresponding parts.

A represents the shell of the valve. B is the valve-stem. C is the nut through which the valve-stem passes, and by which the valve is operated. D is a stuffing-box around the valve-stem. E is the hand-wheel. F is a disk, permanently attached to the end of the valve-stem. G is the ring-valve, which is loosely held on a shoulder on the disk F by a loose washer, H, and a screw, J, which enters the stem by a screw-thread, as seen in the drawing. As seen in the drawing, the valve is closed. The pipes which convey the liquid or fluid are attached to the shell at L L. m represents a wedge, which is attached to the shell, upon one side of the seat, with its point or narrow end up or pointing toward the valve-stem. As before stated, the ring-valve is open, and a wedge-shaped piece removed to correspond with the wedge. In the cross-section, (fig. 2,) the ring and wedge are seen in contact, as when the valve is closed.

It will be seen that the open portion of the ring being forced by the screw-stem on to the stationary wedge, the ring will be expanded and tightly close the apertures *ff*, when it reaches a point near the bottom of its seat, as seen in fig. 1. The ring may pass in loosely, and be less in diameter than the seat, but at the right point the wedge will expand it, so that it will form a tight joint. Provision is made for any wear, either in the ring or wedge, by a space, *g*, below the ring. This valve never needs grinding, has a vertical motion only, or does not revolve, and it leaves a clear and unobstructed passage for the flow of the liquid.

Having thus described my invention, I claim as new, and desire to secure by Letters Patent—

1. The combination of the wedge *m*, shell A, and valve G, substantially as herein shown and described.
2. The combination of the ring G and the wedge *m*, substantially as herein set forth.

EDWARD A. ROCK.
